THUMBTACK EXTRACTOR

Ira L. Thompson, Houston, Tex.

Application September 27, 1949, Serial No. 118,070

3. Claims. (Cl. 254—21)

1

This invention relates to a thumb tack extractor, and more particularly to a novel thumb-tack-extracting device having provision for removing a thumb tack or the like and means for restraining the removed tack in a container.

It is an object of this invention to provide a thumb-tack-extracting device of the kind to be more particularly described hereinafter, having a receptacle for containing thumb tacks before application for use and for collecting thumb tacks immediately upon removal from engagement with a board or the like.

Still another object of this invention is to provide a device of this kind which is formed as a handy manual tool for both pressing thumb tacks into engagement with a board or the like and operable also as a hand tool for readily removing the thumb tacks.

A further object of this invention is to provide a combined thumb-tack-applying and removing tool which is readily operable by one hand of a user for pressing the tack into a selected tack-receiving work piece and also for removing the tacks by manipulation of one hand of the user, thus preventing the customary use and breakage of fingernails or the necessity of separate driving and removing tools. With the use of this tool in removing a thumb tack, the tack is immediately confined within the collecting receptacle as it is drawn from the member within which it had been penetratively engaged.

With the above and other objects in view, my invention consists in the arrangement, combination and details of construction disclosed in the drawings and specification, and then more particularly pointed out in the appended claims.

In the drawings:

Figure 1 is a side elevation of a thumb tack tool constructed according to an embodiment of my invention, shown in its use as a hammer for driving a thumb tack into a work piece;

Figure 2 is a top plan view;

Figure 3 is a side elevation, partly broken away and partly in section;

Figure 4 is a front elevation, partly broken away and partly in section;

Figure 5 is a fragmentary longitudinal section showing, in detail, the hinged connection of the spring-pressed top or cover;

Figure 6 is a side elevation, partly broken away and partly in section, showing the tool applied as an extractor;

Figure 7 is a fragmentary, detail, perspective view of the tack-engaging edge of the front wall of the container.

2

Referring to the drawings, the numeral 10 designates generally a thumb-tack-applying and removing or extracting tool constructed according to an embodiment of my invention. The tool 10 is used as a composite or combined tool to obviate the necessity for the use of separate tools in applying and removing thumb tacks, and obviously will preclude the possibility of damaging or injuring one's fingernails in removing thumb tacks and the like from a board or work piece with which the thumb tack T has been penetratively engaged.

The tool 10 is formed with a substantially cubical receptacle 11 open at the upper end thereof having a handle 12 fixed on one end wall thereof. The receptacle 11 is formed with a bottom rectangular floor or wall 14, a rear end wall 15 extending perpendicularly upwardly from the rear edge of the bottom wall 14, and a front end wall 16 extending perpendicularly upwardly from the front edge of the bottom wall 14 substantially parallel to the rear end wall 15. A pair of longitudinally-extending side walls 17 are fixed to or formed on the bottom wall 14 and engage at their opposite ends with the respective side edges of the front and rear transverse walls 16 and 15, respectively. The bottom, side and end walls define a substantially cubical receptacle 11 open on the upper side thereof.

The handle 12 is fixedly secured to the rear end wall 15 adjacent the upper transverse edge thereof in a manner whereby the receptacle may constitute a hammer head or mallet for driving thumbtacks T into a drawing board B, or other suitable member adapted to penetratively receive the thumb tacks. Generally, however, the tack T will be pressed into the work piece by the finger pressure of an operator on the top of the receptacle 11.

For removably securing the thumb tack T on the receptacle 11, a suitable magnet 18 is fixedly secured on the forward end of the bottom wall 14 on the lower side thereof. The magnet 18 is formed with a concave lower side 19 for smoothly engaging the conventional convex head H of the thumb tack T. When the tack T is drawn into engagement with the face 19 of the magnet 18, the engagement of the convex head H with the concave face 19 will provide for the ready positioning of the tack T at a selected angle to be engaged into the work piece B. When the point P of the tack is penetratively engaged in the board B, the tool 10 may be readily disengaged from the tack by the application of an upward

force on the handle 12 to separate the magnet 18 from the tack T.

The front wall 16 of the box or receptacle 11 is formed with a triangular- or wedge-shaped cut-out portion 20 midway across the length of the upper edge thereof. The side edges 21 and 22, converging downwardly in the front wall 16, define confronting jaws for engagement with the opposite sides of the shank portion or point P of the thumb tack. The flat jaws 21 and 22, converging downwardly on the front wall 16, are spaced apart at their upper ends defining a tack-receiving passage within which the shank of the tack will be received when it is desired to remove the tack from the board B. The jaws 21 and 22 will be slidably engaged between the lower side of the tack head H and the board B, with the shank disposed downwardly along the cut-out 20 as far as possible. A rearward or downward, pivotal movement of the handle 12 about the rear bottom corner of the container 11 as a fulcrum will lift the jaws upwardly and pull the tack T from the board B.

A cover plate 24 is pivotally mounted on the rear end of the container 11 for closing the upper open side thereof. The closure 24 is formed with a horizontal, top, flat plate 25 overlying the upper edges of the side and end walls. A flange 26 depends from the front and side edges of the plate 25 and overlies the outside surface of those walls in the closed position of the cover 24. The flange overlying the front wall 16 partially closes the notch 20 and completely closes the upper open end thereof, in the closed position. A transverse pivot or hinge pin 27 is engaged through the rear ends of the flange 26 and through the upper rear ends of the side walls 17 for hingedly mounting the cover for swinging from an open to a closed position. A spring 28 is coiled about the pin 27 and one end of the spring engages the upper edge of the rear wall 15, while the other end engages the lower side of the plate 25 rearwardly of the pin for biasing the cover to a closed position.

When the extractor 10 is used as such, the cover is initially opened, as noted in Figure 6 of the drawings, while the jaws 21 and 22 are engaged under the tack to be pulled. As the cover is biased to the closed position when the tack is drawn from the board B, the cover will confine the snapping or suddenly-released movement of the tack to the interior of the receptacle, thus limiting the uncontrolled flying of the tack and precluding the necessity for a search for the drawn tack after it has been removed from a board B.

A handle bar 29 is fixed on the closure plate 25 and extends rearwardly and normally upwardly inclined over the handle 12. The bar 29 extends upwardly and rearwardly from the hinge pin 27, whereby, upon swinging the bar 29 into overlying, abutting, or closely-overlying relation to the handle 12, the cover 11 will be swung to the open position. The spring 28 will normally bias the cover 11 closed and the handle bar 29 to rearwardly-divergent relation to the handle 12.

I do not mean to confine myself to the exact details of construction herein disclosed, but claim all variations falling within the purview of the appended claims.

I claim:

1. A tack tool comprising a hollow receptacle having a bottom wall, opposing upstanding side walls and an upstanding front and rear wall, a handle projecting outwardly from the rear wall for swinging said receptacle, an upwardly divergent V-shaped notch formed on the upper edge of the front wall thereof for extracting a tack from a workpiece, the lower edge of the front wall forming a fulcrum about which the receptacle is swung by the handle to extract a tack from a workpiece and a spring urged closure pivotally mounted at one end on the upper edge of the rear wall and adapted to form an upwardly and outwardly swingable upper wall for the receptacle for confining an extracted tack within the receptacle as it is being extracted.

2. A tack tool comprising a hollow receptacle having a bottom wall, opposing upstanding side walls and an upstanding front and rear wall, a handle projecting outwardly from the rear wall for swinging said receptacle, an upwardly divergent V-shaped notch formed on the upper edge of the front wall thereof for extracting a tack from a workpiece, the lower edge of the front wall forming a fulcrum about which the receptacle is swung by the handle to extract a tack from a workpiece and a spring urged closure pivotally mounted at one end on the upper edge of the rear wall and adapted to form an upwardly and outwardly swingable upper wall for the receptacle for confining an extracted tack within the receptacle as it is being extracted, said closure having an actuator for moving it to an open position projecting outwardly therefrom and overlying the handle.

3. A tack tool comprising a hollow receptacle having a bottom wall, opposing upstanding side walls and an upstanding front and rear wall, a handle projecting outwardly from the rear wall, an upwardly divergent notch formed vertically in the upper edge of the front wall for extracting tacks from a workpiece, the lower edge of the front wall forming a fulcrum about which the receptacle is moved by the handle, and a closure pivoted at one end to the upper edge of the rear wall for swinging movement upwardly and outwardly from the receptacle, resilient means normally retaining the closure in a closed position on the receptacle to form a top wall therefor, and an angular handle extending from the closure and overlying the handle for swinging the closure to an open position as a tack is being extracted to form a baffle for directing the extracted tack into the receptacle.
